GRINDING MILL

Willy Köhler, Neckarhausen/Ladenburg-on-the-
Neckar, Germany, assignor to Joseph Voegle
A. G., Mannheim, Germany

Application April 5, 1934, Serial No. 719,177
In Germany April 10, 1933

2 Claims. (Cl. 83—12)

This invention relates to improvements in wet grinding mills in which the material to be ground passes between several smooth surfaced rolls in the form of a paste or thick fluid. After each 5 grinding stage the material under treatment is freed or liberated into a collecting space from which it passes to the next grinding stage. Even such repeated grinding and loosening of the material is not found to be adequate to ensure uniformly fine grinding on the one hand and on the other hand this method of treatment fails to liberate undesirable volatile constituents which impart say, a disagreeable odour to the product. These second mentioned considerations apply in 15 cases such as the fine grinding of chocolate and cocoa beans, so that in many such cases it is necessary to pass the material through a separate stirring process which ventilates the material and enables the volatile constituents to pass off.

20 The object of the present invention is to enable a very high degree of uniform fineness to be obtained in the product from such grinding mills and also in connection with this grinding operation at the same time to free the material of undesirably smelling constituents all in a single pass through the machine.

The invention consists of a grinding mill having a plurality of rolls forming a succession of grinding pairs through which the material is 30 passed in series with collecting chambers for the material interposed between each grinding stage and which is characterized by the provision of stirring mechanism in the collecting chamber between any grinding pair and the next following pair in the series.

The effect of the interposition of this stirring mechanism is to subject the material which has just left or been liberated from one grinding pair to a mixing and breaking up operation which 40 loosens the fine particles and liberates any undesirable volatile constituents and at the same time this loosening has the effect of increasing the grinding or comminuting action at the next following grinding pair.

45 The invention is illustrated in the accompanying drawing by way of illustration in a diagrammatic fashion, it being evident that the details of the grinding and stirring mechanism form no important feature of this invention and may be 50 varied in a number of ways to suit different purposes and materials under treatment. The diagram shows a form of the invention in cross section.

In carrying the invention into effect according 55 to the form illustrated, a single hopper *a* is ar-

ranged to accommodate the material under treatment in the various stages of the series of grinding operations, which are shown as carried out by three grinding rolls *b*, *c* and *g* with smooth cylindrical surfaces. The rolls are in any usual 5 manner held in contact under pressure and rotate with different surface speeds. The roll *b* is supported wholly within the hopper *a* whilst the roll *c* forms part of one side wall of the hopper and the roll *g* forms the base of the hopper. The 10 sloping sides of the hopper walls together with the rolls *b* and *c* form the collecting chambers for the material which, although in the form of a paste or thick fluid must be considered as in the coarse state relatively to the fine state of 15 the finished product. The coarse product is shown at *k*. The first stage of the grinding takes place between the rolls *b* and *c* where the surface of one of the rolls moves at a greater speed than the surface of the other so as to give a 20 rubbing or grinding action. After leaving the grinding point, the surfaces of both rolls are cleaned by passing scrapers *d* and *e* which may, if desired be arranged so that their pressure on the roll surface may be adjusted from outside. 25 This action loosens the material from the roll surfaces but does not break up the smaller cakes or clumps of material. The material *f* so loosened is in a finer state of comminution than the material *k* in the hopper compartment in front of the 30 grinding pair *b* and *c*.

It will be understood that the side walls of the hopper *a* are arranged so close to the rolls *c* and *g* that none of the material can escape.

The provision of the above described loosening 35 means, that is scrapers *d* and *e* on the roller pairs *c* and *b* is known, but in accordance with this invention a stirring device *i* is provided in the collecting chamber for the material *f* which has been loosened or scraped from the roll surfaces 40 by the scrapers *d* and *e* and this stirrer further breaks up or loosens the powder or paste and brings it to a more uniformly thick liquid consistency free of lumps or cakes before the material *f* passes to the grinding stage between the 45 pair of rolls *c* and *g*.

This active stirring operation thus ensures that the small solid particles are relatively displaced and separated to open them up to the maximum grinding action at the next following 50 stage. If the material, as is frequently the case, has been squeezed into the form of flakes or scales these are brought by the stirrer into a position throughout the mass which is in the great majority of cases either at right angles or 55

at some inclined angle to the opening between the rolls of the next following grinding pair, whereas in former designs these flakes entered the second grinding pair more generally in a tangential path. In this way it is possible by means of this invention to decrease the pressure between the second pair of grinding rolls and in fact this pressure does not require to be materially greater than that between the first pair. The 5 comminution effected is nevertheless much greater owing to the fact that the pressure is applied to the flakes more or less always in an "end on" position. The power consumption of the mill is thereby reduced.

15 What I claim is:

1. A grinding mill for use in grinding generally fluid material possessing undesirable volatile constituents, said mill including three grinding rolls cooperating to provide two grinding 20 pairs between which all of the material is passed in succession, an open chamber in constant communication with the atmosphere, said chamber being disposed in proximity to the discharge from the first grinding pair and being also disposed in proximity to the intake of the second 25 grinding pair, a generally stationary scraper operatively bearing against one of the rolls constituting the first grinding pair and arranged to scrape material therefrom and into said open 30 chamber, said scraper being transversely spaced from a wall of said open chamber to permit the undesirable volatile constituents of the material in said chamber to escape between said scraper and said chamber wall to the atmosphere, and a 35 rotary stirrer separate from said scraper for agitating the material in said open chamber and for releasing said undesirable volatile constituents therefrom, said stirrer being disposed within said chamber, and transversely spaced from the sur-

faces of the said rolls and the adjacent chamber walls, and rotatable about an axis generally parallel to the axes of said rolls, said stirrer having a surface movable into proximity to said grinding rolls to feed the material passed between the 5 first grinding pair towards the bite of the second grinding pair.

2. A grinding mill for use in grinding generally fluid material possessing undesirable volatile constituents, said mill including three grinding rolls 10 cooperating to provide two grinding pairs between which all of the material is passed in succession, the adjacent surfaces of the rolls constituting the first grinding pair travelling in the same direction, an open chamber in constant 15 communication with the atmosphere, said chamber being disposed in proximity to the discharge from the first grinding pair, and being also disposed in proximity to the intake of the second grinding pair, and a rotary stirrer for agitating 20 the material in said open chamber and for releasing said undesirable volatile constituents therefrom, said stirrer being disposed within said chamber and transversely spaced from the surfaces of the said rolls and the adjacent chamber 25 walls, and rotatable about an axis generally parallel to the axes of said rolls, the direction of rotation of said stirrer being opposite the direction of rotation of the first grinding roll, and said stirrer having a surface movable into proximity 30 to said grinding rolls to feed the material passed between the first grinding pair towards the bite of the second grinding pair, whereby the material discharged from between the first grinding pair and entering said open chamber will be moved by said stirrer towards the bite of the second grinding 35 pair along a path other than the shortest route.

WILLY KÖHLER.
